CALL TRANSMITTER

Judson O'D. Shepherd, Atlanta, Ga.

Application December 19, 1940, Serial No. 370,761

2 Claims. (Cl. 177—380)

This invention relates to telephone call transmitters and more specifically to call transmitters of the finger wheel operated type.

In call transmitters now in use, a finger wheel is provided with ten finger holes disposed in registry with digits, or groups of letters and digits, in combinations printed on the face of a number plate, one group comprising a cipher and the word "operator," the word "operator" representing ten impulses used for calling the operator at the central office district.

In certain localities a telephone service is rendered which requires that all calls, or those from particular telephones, must be routed at the automatic central office through an operator by the signaling of the word "operator" in the ordinary manner. In call transmitters now in use it has been found that subscribers are liable to initiate any desired call without being routed at the automatic central office to the operator for the reason that in these call transmitters the impulse mechanism is always responsive to any selective operation of the finger wheel.

The object of the invention is to provide a telephone call transmitter which will be simple, efficient in use and in which the movement of the finger wheel is rendered effective only in the signaling of those digits which, individually, involve the transmission of more than a predetermined minimum number of pulses.

In the drawings,

Figure 1 is a plan view showing the finger wheel in normal position.

Fig. 2 is a side view showing a number of operating parts in vertical section taken on line 2—2 of Fig. 1.

Fig. 3 is a top view shown with the finger wheel removed from its supporting shaft and a number of operating parts with portions cut away, the driving clutch element carried by the finger wheel being shown disengaged from its driven associated clutch element;

Fig. 4 is a view similar to that of Fig. 3 shown with the driving and driven clutch elements in engaged relation following the movement of the finger wheel from normal to operated position as limited by the finger stop;

Fig. 5 is a partial view showing the driving clutch element carried by the finger wheel held disengaged from its associated clutch element following a small angular movement of the finger wheel toward its operated position;

Fig. 6 is a partial view shown in vertical section taken on line 6—6 of Fig. 5;

Fig. 7 is a partial view in vertical section taken

on line 7—7 of Fig. 3 showing the pawl which limits the direction of the pulsing cam to one direction in engaged relations with this cam;

Fig. 8 is a plan view shown with a number of operating parts with portions cut away to show the retaining pawl and the pulsing pawl in engaged relation with the pulsing cam;

Fig. 9 is a partial view of the call transmitter showing a modification of the clutch pawl actuating mechanism, the pawl being shown disengaged from its operatively associated clutch wheel; and

Fig. 10 is another partial view showing the clutch pawl in engaged relation with the clutch wheel.

The call transmitter of this invention may consist, for example, of a casing 10 having a centrally disposed bearing 11, best seen in Figs. 2, 6 and 7, in which a shaft 12 is rotatably mounted, and on the periphery of bearing 11 is mounted for rotary movement thereon, as a unit, the gears 13 and 13—A provided for a purpose which will be hereinafter described in detail. Bearing 11 is provided with a reduced portion for rotatably mounting, as a unit thereon, in superposed relation to gears 13 and 13—A a pulsing cam 14 and a clutch element in the form of a notched wheel 15. To the upper end of shaft 12 is keyed a finger wheel 18 having a finger hole H through which the call designation

(Operator)
0

for example, may be visually observed, such designation being printed on a number plate NP sup-

35 ported by a ring 25 formed with three supporting arms 26, 27 and 28 secured to the casing 10 by a number of screws 29, the supporting ring having a stop arm 41 cooperating with the head of a screw 40 carried by the finger wheel 18 for holding this finger wheel in its normal position against the normal tension of a motor spring 17.

To the lower end of shaft 12 is keyed a gear 16 to which one end of motor spring 17 is secured while the other end of this spring is hooked to 45 the casing 10 as shown in Fig. 2, so that the rotation of finger wheel 18 from normal position shown in Fig. 1 to the fully operated position as limited by a finger stop 37 as indicated in dotted line in Fig. 4 is effective to tension the 50 motor spring 17, the function of which is to return the finger wheel to normal position while actuating the pulsing cam 14 in a manner which will be hereinafter described in detail.

The gear 16 meshes with a pinion 19 provided 55 for imparting movement to a pinion 20 through

a one-way effective clutch in the form of a helical spring 21 wound on the hub portions 19—A and 20—A of pinions 19 and 20, respectively, as shown in Fig. 2. Pinion 20 in turn meshes with gear 13—A moving as a unit with gear 13 on bearing 11. The gear 13 engages pinion 30—B shown in Figs. 2 and 3 mounted for rotation as a unit with a gear 30—D on a spindle 30—C journaled in the base 10 and a ring 25, the gear 30—D in turn engaging a pinion 30—E provided for actuating the weights W and W₁ of a centrifugal governor serving for controlling the operation of the pulsing cam 14 during the return movement of the finger wheel 18 under the tension of motor spring 17, the movement of the finger wheel being imparted to the cam 14 through a driving clutch element in the form of a spring-pressed clutch pawl 22 pivoted to the under-side of finger wheel 18 on the screw 40, and the notched wheel 15, the engagement and disengagement of these clutch elements being effected according to the direction of movement of the finger wheel by the cooperation of a cam 30 and a band or split rim 30—Y formed with a ring 23 itself secured to the supporting ring 25.

A double-armed lever or pawl 31 which is pivoted on a spindle 32 journaled in brackets 33 and 34 of casing 10 is provided with a retractile spring SP, shown in Fig. 2, for yieldably holding one arm of this pawl in operative relation with the pulsing cam 14, while its other arm extends in engageable relation with an operable pulsing spring 35 for operating it upon the rotation of cam 14. The spring 35 together with its associated contact spring 35—A is mounted in a pile-up arrangement on a bracket 34 shown in Fig. 2 and provided with terminals T₁ and T₂ to which are attached conductors C₁ and C₂ of an external circuit to be pulsed.

The finger stop 37 is secured to the rim portion of casing 10 by screws 38, to serve for limiting the angular movement of the finger wheel 18 from its normal position shown in Figs. 1, 2 and 3 to its operated position shown in dotted line in Fig. 4.

To the under-side of supporting ring 25 as shown in Figs. 2, 3, 7 and 8 is mounted a pawl 45 held in engaged relation with the pulsing cam 14 by a spring SP₁ for limiting the movement of this cam to one direction for a purpose which will be hereinafter described in detail.

In a typical example of operation of the call transmitter of this invention, the angular movement of finger wheel 18 and the clutch pawl 22 carried thereby from normal position, best seen in Figs. 1, 3 and 8, to its operated position as determined by the finger stop 37, as shown in dotted line in Fig. 4, is effective to tension the motor spring 17 and causes the clutch pawl 22 due to the shape of cam 30 to move first onto the periphery of clutch wheel 15, as at point P₂, shown in Fig. 3, from which point this pawl is cammed onto the periphery of rim 30—Y formed with ring 23 against the tension of its retractile spring X as effected by the camming end of that ring, thus rendering the movement of the finger wheel ineffective relative to clutch wheel 15 to a point CD of that rim where the clutch pawl 22 is caused to engage, for example, the notch B₁ under the tension of its retractile spring X. The movement of finger wheel 18 in its clockwise direction, i. e., from normal position to operated position is effective to rotate the gear 13 and thereby the pinion 19 in a direction ineffective relative to clutch spring 21, so that pinion 20, the gears 13—A and 13 and the unit formed

of pinion 30—B and gear 30—D, and the speed governor connected to the latter gear are not actuated.

Upon the release of the finger wheel 18 by the operator, this wheel is returned to normal position under the tension of motor spring 17, thus rotating the clutch wheel 15 and the pulsing cam 14 carried thereby due to the engagement of pawl 22 with wheel 15, the rotation of pulsing cam 14 being effective to actuate the double armed lever 31 and thereby the pulsing spring 35 ten times, the number of pulses corresponding to the number of teeth of cam 14, i. e., the call designation

(Operator)
0

The speed of rotation of this cam is controlled by the centrifugal governor having its driving pinion 30—E actuated from gear 16 through pinion 19, the clutch spring 21 now effective to operate the pinion 20, engaging the gear 13—A movable as a unit with gear 13 and in mesh with pinion 30—B rotating as a unit with gear 30—D in turn engaging the pinion 30—E of the speed governor.

Upon the engagement of clutch pawl 22 carried by the finger wheel 18 with the cam portion 30 which occurs a small angular distance from the normal position of the finger wheel, the pawl 22 is cammed out of engagement from notch B₁ of clutch wheel 15, while the finger wheel continues its movement as limited by the stop afforded by the head of screw 40 carried by the finger wheel in the path of the upwardly extending lug 41 formed with the supporting plate 25 as shown in Fig. 2, and this cycle of operation is repeated for each call

(Operator)
0

transmitted.

The pawl 45, Fig. 3, pivoted on supporting ring 25 and spring pressed against the impulse wheel 14, is provided to prevent subscribers from calling any other digit than the one authorized. This pawl accomplishes this function by preventing a subscriber from allowing the finger wheel to be returned part way back to normal under the tension of the motor spring and then interrupting its movement and rotating it back to the finger stop and releasing it again in an attempt to dial call designations other than

(Operator)
0

which are not routed to the operator at the automatic central office, for example.

In the modification shown in Figs. 9 and 10, the supporting plate 25 is provided with an upwardly extending cam 50 which cooperates with the cam 30, also formed with this supporting plate, for imparting pivotal movement to the clutch pawl 22 for engaging it and disengaging it from the clutch wheel 15 depending upon the direction of rotation of the finger wheel 18, the pawl 22 being yieldably held in each position by a spring 51 hooked to the pawl 22 by a pin 52 and to the finger wheel 18 by a pin 53, in the manner of a toggle mechanism.

In an example of operation of this modification and considering the pawl 22 in position shown in Fig. 9, the movement of the finger wheel 18 to its operated position as determined by the finger stop 37 is effective to move the pawl 22 to a point where the pin Y carried thereby engages the cam 50 which causes a pivotal move-

ment to the pawl 22 until the longitudinal axis of spring 51 passes the center of pivot screw 40 to cause the automatic continued movement of this pawl under the tension of spring 51 to a point where the pin Y carried by this pawl engages one of the notches b as the case may be.

The release of finger wheel 18 and its consequent return movement to normal position is effective to rotate the clutch wheel 15 and the pulsing cam 14 for actuating the pulsing pawl 31 in the manner above described in connection with the call transmitter shown in Fig. 1. Upon the engagement of pin Y of pawl 22 with cam 30 this pawl is pivoted to a point where the spring 51 again passes on the other side of the center of pivot screw 40 to hold this pawl in the position shown in Fig. 9 and the transmitter is now ready for a subsequent operation.

It is to be noted that the uncontrolled return movement of the finger wheel 18 is prevented by the operation of the governor mechanism from any angular position the finger wheel may have been moved from normal position and this independently of the operation of the pulsing cam.

While the invention has been shown and described in certain particular embodiments, it will be understood that it may be embodied in other organizations without departing from the spirit of the invention and the scope of the appended claims.

What is claimed is:

1. In a call transmitter, a shaft rotatable in two directions, a finger wheel and a gear keyed to said shaft for movement in both of said directions, a casing, a hub element secured to and projecting from said casing and serving as a bearing for said shaft, a motor spring having one end hooked to said casing and its other end to said gear to be tensioned by the movement of said gear in one of said directions, a notched wheel-pulsing cam unit mounted for free rotation on said hub element, a pawl mounted on said finger wheel associated with the notched wheel of said unit, a retractile spring therefor, a stationary ring secured to said mounting and having a ridge, a cam carried by said ring cooperating with means formed with said ridge for controlling the operation of said pawl in one direction of rotation of said finger wheel for guiding said pawl onto the outer periphery of said ridge, and at the termination of said movement guiding it inwardly of said ridge into engagement with a

notch in said wheel under the tension of said retractile spring, said finger wheel being restored to normal by said motor spring upon its release and, due to said pawl engaging said notch, driving said notched wheel-pulsing cam unit, a pair of gears mounted for free rotation as a unit on said hub element, a pinion engaging one of said gears in said gear unit, a pinion engaging the gear keyed to the shaft, a one-way friction clutch 5 operatively connecting the first and second mentioned pinions for rotating said gear unit upon the movement of said finger wheel as imparted by the tension of said motor spring, and a governor mechanism actuated by the other of the pair of gears in said gear unit for governing the speed of said pulsing cam.

2. In a call transmitter, a casing, a hub element carried by said casing and extending perpendicularly on both sides thereof, a shaft 20 mounted for free rotation in said hub element, a pair of gears secured to each other as a unit and mounted for free rotation on said hub element, a notched wheel-pulsing cam unit mounted for free rotation on said hub element in superposed relation to said gear unit, a finger wheel keyed on one end of said shaft, a motor spring tensioned by the movement of said finger wheel in one direction for moving said shaft in the other direction, a gear keyed on the other end of said shaft, 25 a pinion engaging one of said gears in said gear unit, a pinion engaging the gear keyed on said shaft, a one-way friction clutch element operatively connecting the first and second-mentioned pinions, a pinion engaging the other gear of said gear unit, a gear movable as a unit with the last-mentioned pinion, a governor mechanism actuated by the last-mentioned gear under the tension of said motor spring for controlling the operation of said notched wheel-pulsing cam unit, 30 a stationary ring disposed concentric to said pulsing cam having a circular ridge and a camming element, a pawl carried by said finger wheel having a retractile spring, said spring cooperating with said ridge and said camming element for causing said pawl to engage a notch in said wheel on the termination of the setting movement of said finger wheel, and a pulsing mechanism actuated by said pulsing cam unit during the restoration to normal of said finger wheel under the influence of said motor spring.

JUDSON O'D. SHEPHERD.
